US00D479456S

(12) **United States Design Patent** (10) Patent No.: **US D479,456 S**
 Murray et al. (45) Date of Patent: ** Sep. 9, 2003

(54) **DRILL**

(75) Inventors: **Christopher J. Murray**, Baltimore, MD (US); **James B. Watson**, Fallston, MD (US); **Weston J. Van Wambeke**, Cockeysville, MD (US)

(73) Assignee: **Black & Decker Inc.**, Newark, DE (US)

(**) Term: **14 Years**

(21) Appl. No.: **29/163,235**

(22) Filed: **Jun. 26, 2002**

(51) LOC (7) Cl. **08-01**

(52) U.S. Cl. **D8/68**

(58) **Field of Search** .... D8/61, 62, 63, D8/64, 65, 66, 67, 68, 69, 70, 57.11, 429, 464, 465, 466, 469, 489; 173/13, 169, 178, 213, 217; 227/8, 114, 120, 130, 136, 142; 310/50; 408/20, 124, 125, 234, 241 R; 451/358
